ATTORNEY

UNITED STATES PATENT OFFICE

OTTO C. MYER, OF OAKLAND, CALIFORNIA

FIREPLACE HEATER

Application filed February 21, 1927. Serial No. 169,940.

The invention relates to improvements provided in fireplace heaters for use in open fireplaces, the objects of which are to provide for greater efficiency and to eliminate many of the troublesome features common with the present type of said heaters.

An object of the invention is to, first, improve the construction of heaters of the type described so as to provide a clear throat over the fireplace and thus eliminate pipes and other obstructions that have a tendency to obstruct the smoke. Second, to provide an improved type of air chamber having the innermost metal surface thereof adjacent to the fireplace shaped into the form of an arc and so arranged with respect to the fireplace as to retard the flame therein and keep same from rapidly going up the flue, thus forcing more heat through the metal and into the air chamber; the arc shaped inner surface of the air chamber further having a tendency to radiate heat out of the fireplace heater, the improved construction of the air chamber thus providing a greater degree of heat for the same amount of fuel consumed and, therefore, enabling the fireplace heater to have a higher efficiency.

Another object of the invention is to provide the rear legs and the sides of the heater with angular shaped corners so that the fire wall of the fireplace heater may be fitted into said corners and incased with mortar and thereby making it impossible for smoke from the fireplace to ever leak into the air heating chamber.

A further object of the invention is to provide the heater with adjustable legs so that same may be adjusted to fit different height fireplaces.

The invention possesses other objects and features of advantage, some of which, with the foregoing, will be made manifest in the following description of the preferred form of the invention which is illustrated in the drawings accompanying and forming part of the application.

It is to be understood that it is not intended to limit the invention to the embodiment shown by said drawings and descrip-

tion as variations may be adapted within the scope of the invention as set forth in the claim.

In the accompanying drawings:

Figure 1 is a vertical sectional view taken on lines A—A of Figure 2 showing one type of fireplace and heater involving the invention.

Figure 2 is a front elevation of the fireplace and heater.

Figure 3 is a perspective view of the heater.

Figure 4 is a horizontal sectional view taken through the air heating air chamber on lines B—B Fig. 2 showing the method of discharging the hot air out of the air chamber around each side of the flue and the fireplace.

Figure 5 is a sectional view taken on line C—C of Figure 3 showing the angular shape of one of the rear legs of the heater.

According to the construction shown, there is illustrated in Figures 1 and 2 an open fireplace of box like structure having inner side walls 6 and a front and rear wall 7 and 8, respectively, it being understood that the width and depth of the fireplace and the smoke flue extending thereabove may be of any proportional size or shape that will best accommodate the invention which will hereinafter be described.

The improved heater is made of a suitable metal and mounted in the fireplace as shown in Figure 1. The numeral 9 designates an improved air heating chamber having the innermost face 10 thereof formed in the shape of an arc and which extends over and above the fireplace so as to prevent the flame from rapidly going up the flue and also to reflect a portion of the heat out of the fireplace.

An air inlet 11 is provided to supply air to the chamber 9 and it is to be noted that said air inlet 11 leads from said chamber 9 to the front side of the fireplace, bringing air to the chamber 9 from the inside and not the outside and thereby preventing any possibility of cold air from the outside blowing through the chamber. The air chamber 9 is further provided with an im-

proved outlet 12 that leads therefrom to and around each side wall 6 as shown in Figure 4. It will, therefore, be particularly observed that the air that enters said chamber 9 passes therethrough around the side walls 6 and out of the openings 12 on each side of the fireplace, thus eliminating all pipes and other obstructions in the smoke flue which has a tendency to retard the 10 smoke and often cause same to come out of the fireplace and into the room that is being heated.

The several legs 14 and 15 of the heater are made adjustable by having each leg 15 made in two separate pieces, the lateral sides of which are adapted to fit against one another, and are provided with a plurality of holes 16 that are adapted to carry a bolt 17 having a nut 18. By moving the legs 20 up or down, they may be easily adjusted as to height and held fastened secure to the heater by simply placing the bolt 17 into one or the other of the various holes 16. As many fireplaces are of different height, 25 the adjustable feature enables the heater to be adjusted to fit any height fireplace. Also, by raising or lowering the front legs 15 in different proportion to the rear legs 14, the angle of the air chamber 9 may be 30 changed to fit different fireplaces and different conditions.

Provision is made to prevent smoke from ever leaking into the air heating chamber 9 by providing angular shaped rear legs 14 and also by extending the top and bottom 35 and side faces 19 of the heating chamber 9 beyond the outermost curved surface 10 of said chamber. These corners thus formed, shown in Figure 3, allows the fire-wall 6 to 40 be fitted into said corners and incased therearound with mortar making an absolute smoke tight joint, positively preventing any smoke from the fireplace leaking into said air heating chamber and finally into the 45 room that is being heated.

A damper 20 of any standard make is provided and located in the smoke flue to regulate the opening therethrough. In the present illustration a standard hinged damper 50 is shown, but a sliding damper, or any other standard type may be used, it being understood that the damper in itself does not constitute a part of the invention.

From the foregoing it will be observed 55 that the heater herein described is simple and practical and has many advantageous features. The air which enters the chamber 9 through inlet 11 is heated as it passes through said chamber and is discharged into the room without, in any way, obstructing 60 the smoke flue, and other heat is reflected into the room by the arc shaped outermost metal surface of the heating chamber.

Having thus illustrated and described a 65 certain form of construction and arrange-

ment of parts pertaining to the invention, it is to be understood that the improvements may be embodied on any type of fireplace heater, which, obviously, may be built up in any suitable manner, the present illustration not being utilized as indicating the only form of construction into which the parts may be made; and it is desired to include in this application for Letters Patent of the United States of America, all 75 that comes within the range of the invention as set forth in the claim hereinafter mentioned.

What is claimed:

The combination with a fireplace structure having a smoke flue and a damper therein, of an air heater mounted in the fireplace; the said air heater comprising an air chamber having an inwardly curved metal face adapted to fit over and above the fireplace; the top and bottom and the lateral side faces of said chamber being adapted to extend beyond said curved face and form inside corners therearound that are adapted to be filled with masonry by walls of the 90 fireplace structure; a plurality of angular shaped legs fastened to the heater; an air inlet leading from the front side of the fireplace and into the lower portion of the air chamber; and an air outlet leading from the 95 upper portion of the air chamber and from the lateral side walls thereof and extending outwardly therefrom beyond each lateral side of the smoke flue and through the front wall of the fireplace structure 100

In testimony whereof, I hereunto affix my signature.

OTTO C. MYER.
